UNITED STATES PATENT OFFICE.

HARRY A. CUMFER AND OWEN D. McFARLAND, OF CHICAGO, ILLINOIS, ASSIGNEES TO GUYTON & CUMFER MANUFACTURING COMPANY, OF CHICAGO, ILLINOIS, A CORPORATION OF ILLINOIS.

METHOD OF MAKING COMPOSITION SHINGLE-STRIPS.

1,276,881.

Specification of Letters Patent. Patented Aug. 27, 1918.

Original application filed January 2, 1915, Serial No. 249. Divided and this application filed November 20, 1918. Serial No. 132,346.

To all whom it may concern:

Be it known that we, HARRY A. CUMFER and OWEN D. McFARLAND, citizens of the United States, both residing at Chicago, in the county of Cook and State of Illinois, have invented certain new and useful Improvements in Methods of Making Composition Shingle-Strips, of which the following is a specification.

10 One of the objects of our invention is to provide a new and useful method of making shingle-simulating strips of flexible material, for roof coverings, and the like.

Other and further objects of our invention will become readily apparent to persons skilled in the art, from a consideration of the following description when taken in conjunction with the drawings, wherein—

Figure 1 is an end elevation of a machine by which our method may be carried into effect, showing a roll of the material of which the strips are made, broken away to expose portions of the machine.

Fig. 2 is an end view, showing the end upon which the power wheel and the connecting and the disconnecting clutch are mounted.

Fig. 3 is a transverse section taken on line 3—3 of Fig. 1 showing the train of gearing for connecting the various rolls and shafts together.

Fig. 4 is an enlarged view of a hollow cylinder, carrying the hollow punches and constantly rotatable to punch slots, at uniform intervals, along the edges of the strips.

Fig. 5 shows a sheet that has been cut into four shingle-simulating strips and transversely-extending punched holes that bridge the slits, located at uniform intervals longitudinally of the strips.

Fig. 6 shows a series of these simulating strips as they will appear when applied to a roof.

In all the views the same reference characters are employed to indicate similar parts.

This application is a division from the application for shingle-strip making machines filed January 2, 1915, and indicated by Serial No. 249.

While our method of making shingle-simulating strips may be accomplished without the aid of a machine, it will be more readily understood in connection with the

description of a machine that is readily adapted for carrying the method into effect.

The material of which our shingle-simulating strips are, preferably, made, consists of felt fabric 12, treated with asphaltum, or the like, and preferably covered on at least one side, with flaky, vitreous or mineral material, such as slate or the like and wound upon rolls 13 supported upon a shaft 14. The machine which may be used conveniently for carrying our method into practice consists of two side frames 15—15', which are substantially duplicates. The side frames are held together by a suitable number of bolts 17 secured in place by nuts 18. Spacing tubes, or pipes 19 are placed over the rods 17—17 as a convenient means for holding the side frames 15—15' parallel. A pair of brackets 20—20' are secured to one end of the frames 15—15' for support of the shaft 14 carrying the roll 13. Beams 21—21' extend between the side frames 15—15' and are preferably T-shaped in cross section, having their flat top surfaces uppermost, which serve as tables for support of the fabric 12, as it passes between the various rolls and rotating punches and dies. The beams are secured to the side frames at each end by screws or bolts 22 and coöperating nuts 23.

Extending between the side frames 15—15' are the parallel shafts 24 and 25. The shaft 25 is supported in relatively stationary bearings 26—26', one on each frame, the shaft 24 being supported at each end in vertically adjustable bearings 27—27'. The hand wheels 28,—28' serve as means for vertically adjusting the relative position of the shafts 24 and 25 in an obvious manner. The rotation of the hand wheels 28, 28' serve to raise or lower the respective ends of the shaft 24 in adjusting it in position with reference to the shaft 25. The bearings 27, 27' have outer squared surfaces adapted to be vertically moved in guide ways 31 provided in the respective housings, or side frames. Each of the shafts 24 and 25, is provided near its respective end with a collar 32 that may be secured to the shaft in adjusted position, preferably against the respective boxes in which these shafts are supported by a screw 33 to prevent axial movement of the shaft. The shafts 24 and

25 are connected together for driving relation by the geared pinions 34 and 35, as by keys 36. These pinions are of the same diameter and contain the same number of 5 teeth and, therefore, the shafts 24 and 25 preferably, rotate at the same speed. Mounted on the shafts 24 and 25 are cooperating feed roller sections 37 and 39 rotatably held in place by feathers that 10 are included in a spline which extends between the bearing ends of the respective shafts. On the shaft 24 is mounted a series of diametrically divided, rotary disk knives 40, of which there may be any desired 15 number, each knife, for convenience of removal and replacement, is divided into two parts 40^a and 40^b. Each of the knife sections 40^a and 40^b, is secured to a sleeve 42 and between the flange 41 of the 20 sleeve and a separable flat ring 43, by means of bolts 44. This particular feature of our invention is disclosed and specifically claimed in a prior Patent No. 1,107,762 granted to Harry A. Cumfer on the 18th 25 day of August, 1914, and therefore is not subject matter for claims in the present application.

A series of knife members 45 contact one with each knife 40 and are located on the 30 parallel shaft 25. Each consists of a sleeve 46 having a radially extending flange 47, which abuts the side of the cutting edge of the knife 40. Each pair of the feed rolls 37, 39 is adapted to feed the individual 35 strip into which the sheet is cut and is counter-bored, to permit the sleeve 46 of the member 47 to enter the counter-bore so as to bring the surface 47 of the feed roll 37 into close approximation with the respective knife. The fabric 12 of the roll 13 is fed directly to the knives 40 by means 40 of the feed rolls 37 and 39, which knives slit the fabric into the desired number of strips, as shown in Fig. 5. There may be 45 as many strips as there are suitable knives mounted upon the shafts 24 and 25. The strips so slit are then passed over the table 21 to the rotary punches, which punch transversely extending slots, or apertures that 50 bridge the adjoining edges provided by the slitting knives, and which may also punch slots into the moving fabric inwardly of the outer boundary thereof.

Mounted upon the shafts 50 and 51 are 55 rotary punches 52 and a coacting drum 53, respectively. The shaft 50 is supported in relatively stationary bearings and the shaft 51 is supported in relatively adjustable bearings 55, 55', vertically movable in the 60 same manner and for substantially the same purpose as the shaft 24, by similar wheels 56, 56'. The punch-carrying shaft 50 is driven from the power shaft 57, which is supported in bearings 58, 58' of the side 65 frame by means of a geared pinion 59

which meshes into a gear wheel 60 carried by the shaft 50. The shaft 51 is driven by the geared pinions 61 and 62 of the same diameter, and having an equal number of teeth, so that the shafts 50 and 51 will be 70 rotated at the same speed; the geared wheels being secured to the respective shafts by keys 63. The rotatable drums 52 which carry the separable hollow punches 64 are hollow, or carry interior recesses. Each of 75 the drums, in the exemplification is provided with four hollow punches 64, and associated with each punch is a recess 65 in the drum structure to receive the parts punched from the fabric and to permit the 80 same to fall away from the punch, as clearly shown in Fig. 3. Each of the punches 64 is secured to the drum by screws 66, so that the punches may be removed, sharpened, and replaced, or new punches provided. 85 The shape of the punch and the arrangement shown in the machine, with the number of knives and punches indicated will produce the fabric shown in Fig. 5. To produce fabrics having perforations of different shape, punches of various configurations may be used and it is only necessary to change the shape of the punch and to vary the positions and numbers of the knives and punches required to change the 90 general form of the strips. The smooth face drum 53 is provided with removable hardened wearing plates 68, 68' of which there may be a suitable number and which are preferably made of better material than 95 the body portion of the drum, may be removed and replaced by means of the screws 69. These plates form the abutment for the fabric when the punches 64 are brought into contact therewith and by this means 100 cooperates with the punches to produce apertures in the fabric as it passes between the punches and drum. The punches engage the under side of the fabric, which is not covered with slate or the like, and push the 105 covered side into contact with the superposed smooth surface of the drum.

Pieces of relatively thin sheet metal 70, 70' are placed on either side of the axis of the shafts 50 and 51 to support the fabric 110 as it passes in between and out from the punches and cylinder die. Each of these pieces is provided with a vertically extending part 71, 71' and is adjustable transversely of the fabric so that the parts 71, 115 71' will support the fabric and prevent the strips that have been separated from the sheet by the slitting knives from separating from each other as they pass between the punch and die. The plates 70 and 70' are 120 so arranged that the vertical portions 71, 71' may be brought into contact with the outer selvage edge of the sheet of fabric of various widths.

Just about the time the fabric is being 130

properly longitudinally severed or slitted by the slitting knives and punched at proper intervals by the punches and dies it passes between the guides 71, 71' and over the tables 21, 21' into and between the feed rolls 73 and 74, which are mounted upon the shafts 75 and 76, respectively. These feed rolls, 73 and 74, may be hollow drums, as shown in Fig. 3, secured to the respective shafts by means of set screws or the like, at their respective ends. The shaft 76 is supported in a stationary bearing and the shaft 75 is supported in vertically adjustable bearings. The shafts 75 and 76 are connected together by means of geared pinions 82 and 83 of substantially the same diameter and containing the same number of teeth which are held on their respective shafts by keys 84. The shafts 75 and 76, are driven by these pinions and an intermediate gear 85 supported on the stud 86 that projects from the frame 15, the intermediate gear 85 is driven by the gear wheel 61. A similar intermediate gear wheel 87 is mounted upon a stud 86' and serves to drive the gear wheel and pinion 35, itself being driven by the gear wheels 61.

Rotatable upon a power shaft 57 is a power wheel or pulley 90, which is adapted to be secured to the power shaft to drive the machine by means of a clutch 91 operated by the handle 92.

A housing 93 covers the train of gearing on one side of the machine and a similar housing 94 covers the train of gearing on the other side of the machine. These housings protect the operator from danger of intermeshing gear wheels.

By the use and operation of the machine, as illustrated, the sheet 12 is fed continuously from the roll 13, and is divided into four strips 12^a, 12^b, 12^c and 12^d. The strips 12^a and 12^b are separated by a slit 95 and this slit, which extends longitudinally of the strip, is bridged by transverse slots 96 which are made before the strip is completed and which may be of any desired form within the contemplation of our method of making shingle simulating strips. These slots are spaced at regular intervals,

or distances apart, and when the strips are assembled the lower portion of them, between the slots, simulate the appearance of separate shingles, as shown in Fig. 6, one strip being laid and lapped upon the other, just as the shingles are separately placed in position. The perforations 96 of the strip provides kerfs or spaces as between adjacent shingles. It will be observed that to hasten the operation of our method of construction the sheets and strips are continuously in motion; that the sheet is first slitted longitudinally to subsequently provide as many strips as is required and then simultaneously punched at intervals, the slots or perforations thus provided breaking the otherwise longitudinally continuous edges of the strip and finally the strips are passed from the machine, in this condition, ready to be divided into suitable lengths. Any suitable means for cutting the strips into equal lengths may be employed.

While we have shown a machine for carrying our invention into effect, it is manifest to persons skilled in the art that our method of making shingle-simulating strips is not dependent upon a machine of any particular construction as it may be carried into effect by hand manipulation but not so rapidly or so cheaply as when a machine is used for the purpose.

Having described our invention, what we claim is:—

The method of making shingle-simulating strips of flexible material for roof covering, which consists in providing a sheet sufficiently wide to make two or more strips; slitting the sheets longitudinally into strips; punching transversely extending openings at uniform intervals across the edge of the severed sheet at right angles to the path of movement of the sheet; holding the severed edges together while being punched, and moving the fabric continuously during the slitting and punching operation.

In testimony whereof we hereunto set our hands.

HARRY A. CUMFER.
OWEN D. McFARLAND.
